UNITED STATES PATENT OFFICE.

WILLIAM SHALLCROSS SPEED, OF LOUISVILLE, KENTUCKY, ASSIGNOR TO LOUISVILLE CEMENT COMPANY, OF LOUISVILLE, KENTUCKY, A CORPORATION OF KENTUCKY.

DRAWING APPARATUS FOR KILNS.

Application filed March 13, 1919. Serial No. 232,502.

To all whom it may concern:

Be it known that I, WILLIAM S. SPEED, citizen of the United States, residing at Louisville, in the county of Jefferson and 5 State of Kentucky, have invented certain new and useful Improvements in Drawing Apparatus for Kilns, of which the following is a specification, reference being had therein to the accompanying drawing.

10 This invention relates to a drawing apparatus for kilns, and is more especially useful in connection with vertical lime and cement kilns.

In a prior patent issued to myself under 15 date of Oct. 11, 1904, No. 772184, there is disclosed a drawing device or apparatus, which has been extensively used with some considerable success, but there are certain disadvantages and objections incident to 20 an apparatus of the character therein illustrated, owing to the fact that the drawing or discharging device is subject to continuous and uniform operation, regardless of the condition or character of the particular 25 material under treatment in the kiln, and it is the primary object of the present invention to overcome recognized objections, and to this end it is proposed to provide a movable drawing device, with means whereby 30 the movement may be accurately regulated at will and adjusted to suit the requirements of proper calcination of the rock, etc., with a view to better efficiency and larger economy in the operation of the kilns.

35 More particularly, the invention includes a drawing device adapted to have a reciprocating or to-and-fro movement beneath the outlet opening of the kiln chamber, and novel and improved operating means for 40 imparting the necessary reciprocating movement, said operating means being adapted to be quickly adjusted whereby to vary the throw of the drawing device, and without the necessity of removing parts or in- 45 terrupting the operation of the kiln.

It is further contemplated by the invention to provide in operative association with the discharge opening of the kiln, a drawing or discharging device, novel supporting means for the discharging device, pivotally mounted actuating rods or links for the drawing device, and means for adjusting the fulcrum for said rods.

Again, an important feature of the in-

vention resides in the provision of a plurality of operatively connected drawing devices for adjacent kilns, and common operating mechanism for the respective drawing devices, and in the preferred embodiment of the invention, said operating mechanism being of a character whereby upon adjustment it will simultaneously adjust the movement of the plurality of drawing devices.

Still further, it is contemplated by the invention, to generally improve upon drawing devices of the character under consideration, and such as represented by my previous patented construction, whereby, to, in a simple and economical manner render said devices more efficient and satisfactory in operation, and strong and durable in use.

Other improvements and novel details in the construction and arrangement of the various parts of the invention, will be appreciated by those skilled in the art from 75 the description to follow, which, for a clear understanding of the invention is to be considered in connection with the accompanying drawings, forming a part hereof, and wherein is disclosed for the purpose of 80 illustration, a convenient and satisfactory embodiment of the invention, though in this connection, it is to be understood that minor changes may be resorted to without departing from the spirit or contemplation 85 of the invention.

In the drawings,

Figure 1 is an elevation of a preferred embodiment of the invention illustrating a plurality of operatively associated drawing 90 devices with operating mechanism therefor applied to adjacent kilns, the latter being shown in section, and parts being broken away.

Figure 2 is a top plan of the drawing devices, separated from the kilns proper, and one of the drawing devices being broken away.

With more particular reference to the drawings, like reference numerals refer to 100 corresponding drawings throughout the several views, in which, 1 represents generally the frame-work of the apparatus, 2 the side walls of a kiln, and 3 the bottom wall thereof. These kilns are preferably 105 arranged in duplicate, as illustrated, with an intervening space 4 for the reception of operating means to be presently de-

scribed. The kilns are adapted to receive the rock 4^a to be calcinated, and each kiln is provided with an opening in the bottom wall thereof communicating with a suitable discharge chute 5. Positioned below the discharge chutes is the continuous draw, preferably constructed substantially as follows: 6 is a horizontally disposed platform or table arranged in the path of the discharging material, the platform having at a point substantially midway of the ends thereof an opening 7 communicating with a discharge chute 8, conveniently projecting laterally and adapted to deliver the material onto a longitudinally extending endless conveyor 9 of any appropriate type projecting at a slight inclination towards the outer end thereof, and disposed at its upper end above a transversely movable conveyor 10 of any suitable type to be discharged therefrom onto cars or the like by means of a suitable chute or chutes not necessary to illustrate or describe herein. The drawing tables are conveniently supported by links 11, conveniently four at opposite sides of the table arranged in pairs, with two pairs at each side of the discharge chute 8. The links are pivotally connected at the top to the table platform 6 and at the bottom to the frame-work 1 in any suitable manner for free oscillating movement. As the table is moved back and forth the link supports have a tendency to cause the material to feed to and gradually discharge through the chute 8. Actuating means for the tables conveniently takes the form of an elongated bar or bars 12 pivoted at the outer end as at 13 to one end of the table and pivotally supported as at 14 to a vertically disposed link 14^a, which latter is connected for vertical adjustment at will, preferably through the medium of an adjusting rod extension 15 pivotally connected to the link as at 16, and having a threaded terminal 17. The adjusting rods for the respective links 14^a project through suitable apertures in the frame-work 1^a and a hand operated nut with interior threads corresponding to the threads of the adjusting rods 15 is positioned on each of said rods and adapted to rest upon a bearing member or washer 18 loosely sleeved on the adjusting rods and adapted to contact with the upper surface of the frame-work 1^a. An elongated drive shaft 19 is provided, the same adapted to receive rotatable motion through the medium of a motor or the like, and having at its inner end a drive pinion 20 adapted to engage a gear wheel 21 mounted on a suitable shaft 22 and carrying a pinion 23 adapted to mesh with the gear wheel 24. The gear wheel 24 has pivotally connected thereto a suitable pitman rod 25 pivotally connected at 26 to the upper end of an actuating member 27 which

latter is pivotally connected at 28 upon a suitable support for swinging movement and has at opposite sides elongated vertically disposed slots 29 for the reception of pins conveniently formed by extensions of 70 the pivotal connection 14 between the adjustable links 14^a and actuating rods or bars 12.

Projecting below the kiln at opposite sides of the discharge chutes 5 are vertically disposed plates 30 extending to a point adjacent the table 6 whereby to constitute contacting parts for the discharged material on the tables and to prevent the same from falling off the outer ends of the tables in 80 the movement of the latter, and whereby to assist in the gradual movement of the material to the discharge openings 7.

The operation may be briefly reviewed as follows:

The lime or other material from the kiln gradually flows by gravity through the discharge chutes onto the oscillating tables or platforms 6 supported by the pivoted legs or links 11, the tables receiving their motion by the actuating rods 12 through the medium of the swinging actuating member 27 driven in the manner fully described by means of the gear operated pitman 25. The pin and slot connection 95 14—29 between the actuating rods 12 and the swinging actuating member 27 provides a shiftable connection, whereby the length of oscillation of the tables or platforms may be accurately controlled by raising or lowering the adjustable links 14^a by means of the adjusting extension rods 15. As the material is drawn onto the oscillating tables it is gradually fed through the chute 8 between the sections of the tables onto the 105 inclined conveyor 9 extending longitudinally of the tables and therebeneath to the end of the kilns, and is then dumped onto a conveyor preferably arranged at right angles to the first mentioned conveyor, and by means of suitable chutes, or other conveyors, etc., is finally discharged preferably directly into an ordinary freight box car for the purpose of transportation.

It has been ascertained that by the use of 115 the present apparatus, the rate at which the kiln may be drawn, may be accurately adjusted to meet the requirements of proper calcination of the rock, and a more efficient operation results.

What I claim is:

1. A continuous drawing apparatus for kilns having a discharge opening in the base thereof, comprising a reciprocating table or platform disposed below said opening, upright pivotal supports disposed below the platform and connected therewith, and means for imparting back and forth movement to the platform, said platform having a discharging chute, and an endless conveyor 130

arranged below, whereby to receive and transport the material discharged from, said chute.

2. A continuous drawing device for kilns having a discharge opening at the base thereof, said device comprising a horizontally disposed platform arranged below and adjacent to the discharge opening of the kiln, upright links pivotally supported at the lower ends and pivotally connected at the upper ends to said platform, and means for imparting continuous back and forth movement to the table relative to said discharge opening, said platform having a discharge opening intermediate the ends thereof, and a conveyor member arranged below said opening of the platform for transferring the material.

3. The combination with a kiln having a discharge opening, of a continuous drawing device arranged below the discharge opening of the kiln, said drawing device having an opening intermediate its ends, and a downwardly directed discharge chute communicating with said intermediate opening, said device being mounted for oscillating movement, and mechanism for imparting continuous oscillating movement thereto.

4. In combination with a kiln having a bottom opening for the discharge of the material, of a continuous drawing device comprising a horizontally disposed platform arranged below said opening, and itself having an outlet opening and a receiving chute projecting therebeneath, a conveyor to receive the material from said chute, and spaced downwardly disposed contacting parts on the bottom of the kiln, one at each side of the discharge opening therein, and projecting to a point adjacent said platform.

5. In combination with adjacent kilns, each of which has a discharge opening in the base thereof, of continuous draw feed devices comprising a platform arranged beneath each kiln discharge opening and mounted for horizontal reciprocation, and common actuating means disposed between the platforms for simultaneously imparting continuous reciprocating movement thereto.

6. In combination with adjacent kilns, separated from one another by an intervening space, the kilns having a discharge opening at the base thereof, a drawing device for each kiln, comprising a horizontally disposed platform arranged beneath the discharge openings of the kiln, upright link supports for the platform, actuating rods for each platform, and means operatively associated with each of said actuating rods for simultaneously imparting continuous reciprocating movement to the platforms.

7. In combination with a kiln having a discharge opening therein, a platform mounted beneath the discharge opening for reciprocating movement and for receiving

the material from the kiln, a pivoted lever having a slot therein, means for operating the lever, a rod having one end connected in the slot and freely movable therein for vertical movement and the opposite end connected to the platform, means for adjusting the end of the rod vertically in the slot and means for discharging the material from the platform.

8. In combination with a kiln having a discharge opening therein, a platform mounted beneath the discharge opening for reciprocating movement and for receiving the material from the kiln, a pivoted lever having a slot therein, means for operating the lever, a rod having one end adjustably connected in the slot of the lever and the opposite end connected to the platform, and means for discharging the material from the platform.

9. In combination with a kiln having a discharge opening, of a continuous draw feed arranged to receive and dispose of the said material, comprising a horizontally disposed platform, a member mounted intermediate its ends for swinging movement, means engaging one end of the member for imparting continuous swinging movement thereto, said member having a vertical slot therein, an actuating link connected to the platform and having a part to engage in said slot of the swinging member, and an adjustable link support for that end of the actuating lever in engagement with the swinging member.

10. In combination with a kiln having a discharge opening, of a continuous draw feed arranged to receive and dispose of the said material, comprising a horizontally disposed platform, a member mounted intermediate its ends for swinging movement, means engaging one end of the member for imparting continuous swinging movement thereto, said member having a vertical slot therein, an actuating link connected to the platform and having a part to engage in said slot of the swinging member, an adjustable link support for that end of the actuating lever in engagement with the swinging member, and upright link supports for the platform.

11. In combination with a pair of kilns arranged adjacent to one another with an intermediate space, each kiln having a discharge opening, a draw feed device arranged beneath each discharge opening and comprising a platform mounted for reciprocation, link supports for the platforms, actuating links projecting inwardly from each platform, a swinging member arranged in the space beneath the kilns and having slots therein adapted to receive a part on the adjacent end of the actuating links, upright links connected to the inner ends of said actuating links, and adjustable extension

rods on said last mentioned links whereby to form a shiftable connection between the actuating links and said swinging member.

12. In combination with a pair of spaced kilns, each having a discharge opening, a horizontal platform mounted below each discharge opening, a lever pivotally mounted between the kilns and having slots therein, a link pivotally connected to each platform at one end and having the opposite end provided with a pin received in one of the slots of the lever, vertically extending rods connected to the pin ends of the links, a cross bar between

the kilns, threaded rods pivotally connected to the first mentioned rods and extending through the cross bar, means carried by the threaded rods and engaging the cross bar for adjusting the connection between the links and slotted lever, and means for oscillating the lever.

In testimony whereof I hereunto affix my signature in the presence of two witnesses.

WILLIAM SHALLCROSS SPEED.
